(57) **CLAIM**

The ornamental design for a task light protection plate for a welding helmet, as shown and described.

DESCRIPTION

FIG. 1 is a perspective view of a task light protection plate for a welding helmet showing our new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

1 Claim, 1 Drawing Sheet
